DOUBLING OF YARNS, THREADS, OR
FILAMENTS

William Pool, Spondon, near Derby, England, assignor to Celanese Corporation of America, a corporation of Delaware

Application October 30, 1931, Serial No. 571,972
In Great Britain December 24, 1930

1 Claim. (Cl. 117—23)

This invention relates to twisting and doubling of yarns, filaments, or threads (hereinafter referred to as "threads") and in particular to twisting and doubling by means of devices adapted to impart more than one turn of twist for each revolution imparted to the devices.

In such devices, the package from which the thread is to be wound does not partake of the revolution of the twisting device. The thread is drawn off the package and made to form a loop which is carried round the package itself by the rotation applied to the device. Assuming the package to be stationary, two turns of twist are imparted for each revolution of the loop about the package. Rotation of the package itself in a direction opposite to that of the loop enables a higher rate of twisting to be obtained for the same rate of revolution applied to the device.

The thread loop may be so guided that it revolves in the open air about the package, following a path varying from practically a straight line to an outwardly bulging curve, depending on the tension to which it is subjected, or it may be constrained to a definite predetermined path by the use of a flyer or the like.

According to the present invention a device of the above character is employed to double together the thread to which the extra twist has been imparted with thread to which no twist is given in the doubling operation. In carrying out the invention, a package of thread to receive the extra twist is mounted in the device, and the thread is led through the device to form a loop which is caused to revolve about the package. Another thread (or threads, though for simplicity it will be assumed hereafter that there is only a single thread) is led to the axis of the device at the end remote from that at which the first thread leaves the device, and is caused to follow a loop-like path so as to revolve about the package in the device. The two threads are drawn together from the device, then being doubled together, the one thread (the "external" thread) not however being twisted.

The external thread may be doubled to the first with a number of turns equal to the twisting turns applied to the device or alternatively equal to the twisting turns imparted to the thread on the package (the "internal" thread). For example, if the external thread simply runs from end to end of the device as a loop which revolves about the package, the lesser number of turns is imparted. If, however, it runs from one end of the device to the other as a loop, and then returns without revolving round the pack-

age to the end where the internal thread leaves the package, the paths followed by both threads cause them to rotate about the package, and the larger number of turns is imparted.

In the first of these cases, the external thread may follow the same path as the internal thread from one end to the other of the device, or it may follow an independent path, the only difference being in the actual point at which doubling of the threads commences. In the second case, it is essential that the path of the external thread be independent of the internal thread in its first run as a loop, while in its second run as a loop it may follow the same path as the internal thread or an independent one.

The doubled threads may be collected by simple winding, or may be further twisted, or doubled with similarly doubled or twisted or other threads by means of a suitable twisting device such as a ring spindle. The degree of doubling twist applied by the device depends, of course, on the rate of take-up of the doubled thread and the rate of twisting.

As mentioned above, more than one external thread may be doubled with the internal thread, the external threads not, of course, being twisted in the operation. More than one internal thread may also be used, two or more packages, or two or more parallel "ends" on a package supplying these threads, which are twisted together as well as doubled with the external thread or threads.

By suitable adjustment of the tensions of the threads to be doubled, the structure of the doubled thread can be caused to vary from a covering of one thread by the other to a spiral or looped arrangement of one on the other or a close intermingling of the internal and external threads. In this way, and by the use of threads of different materials or characteristics, e. g. threads of cellulose acetate with threads of wool, silk, cotton, or cellulosic artificial silk, a large variety of doubled threads may be produced. Further, the rate of take-up may be adjusted relatively to the rate of twisting that the thread may have a degree of doubling varying from low to high or very high. A variable rate of take-up enables threads of intermittently varying doubling twist to be produced.

Any suitable form of twisting device may be used provided it has means for the introduction of the external thread as well as means for leading the doubled internal and external threads away. Conveniently the twisting device has two or more symmetrically arranged tubular flyers through which the threads are led. When the

internal and external threads are doubled together with the larger number of turns possible, the external thread first passes independently through one flyer, and after passing through the 5 axis of the package, is led through another flyer, which may be the same as that through which the internal thread passes.

In order to lead the threads into and away from the twisting device, the device has a hollow 10 spindle at each end, the flyers being connected to these spindles in such a manner that the thread can be drawn through the spindles and flyers without excessive tension.

Each spindle may be mounted in ball or other 15 bearings, or the flyers may be made sufficiently strong to carry one spindle without the provision of a bearing for that spindle. The device is driven by means such as belt or other gearing or an electric motor coupled to the spindle. The 20 internal package or packages may be held stationary, or substantially so, by friction wheels carried bodily round by the driven spindle and engaging respectively a race on the package support and a fixed race independent of the package, as described in U. S. Patent No. 1,949,621.

Alternatively, gears may be used in place of the 25 friction wheels and races described above, and again, such gears or friction devices may be used to rotate the internal package or packages, preferably in such a direction as will increase the rate of doubling. Such devices may be arranged with 30 vertical, inclined, or horizontal axes. The device may however be arranged with a horizontal or inclined axis and the internal package kept stationary by gravity by having its centre of gravity below the axis of rotation of the device.

The invention will now be described with reference to the accompanying drawing, but it is to be understood that this description is given by 35 way of example only, and is in no way limitative.

Fig. 1 shows one form of driving arrangement for the twisting device used for the purpose of the invention;

Fig. 2 shows an alternative form of driving 40 device;

Fig. 3 shows the lay-out of a twisting device used for doubling the threads to a low degree of 45 doubling twist;

Fig. 4 shows an arrangement for doubling the 50 threads to a high degree of doubling twist; and

Fig. 5 shows another arrangement for doubling the threads to a low degree, one of the threads being taken from outside the twisting device.

Referring to Fig. 1, one or more bobbins 8 are 55 mounted on brackets 9 carried upon a platform 10. The platform 10 is fixed to a hollow spindle 11, carried by means of ball bearings 12 in an enlarged portion 13 of a further hollow spindle 14. The spindle 14 is mounted in ball bearings 15 60 and is driven by means of a whori 16. A short spindle 18 is supported by ball bearings 17 in the enlarged portion 13 of the spindle 14, the spindle 18 being parallel to the axis of the spindle 14, and having gears 19, 20 fixed to its upper and lower 65 ends respectively. The gear 19 meshes with a further gear 21 attached to the spindle 11 carrying the platform 10, while the gear 20 at the lower end of the spindle 18 meshes with a gear 22, rigidly fixed to the frame of the device. The 70 gears 19 and 20 being of the same size, and the gears 21 and 22 being also of the same size, the rotation of the spindle 17 about the axis of the spindle 14 causes the gear 21 to remain stationary like the gear 22, with the result that the platform 10 and the package 8 are held sta-

tionary, and are not permitted to rotate with the spindle 14. The frame of the device to which the gear 22 is fixed rises in a flange 25 to enclose the gears 20, 22 and in a similar manner the enlarged portion 13 of the spindle 14 rises in a flange 26 to enclose the gears 19 and 21.

The enlarged portion 13 of the spindle 14 also carries two flyer tubes 27, 27' communicating with the hollow interior of the enlarged portion 13, the flyers passing out of the portion 13 from points lying at right angles to the points at which the spindles 17 are carried. For this reason the flyer 27 on the left of Fig. 1 is shown in dotted lines, since the section on which this figure is taken is on two lines meeting at right angles at the centre of the spindle, so that the flyer 27' does not actually lie in the section shown.

An alternative form of driving device producing the same effect is shown in Fig. 2. In this case the platform 10 is mounted on ball bearings 12 surrounding a spindle 43 which has an enlarged portion 44 and is driven by means of a whori 45. The enlarged portion 44 of the spindle 43 contains horizontal passages 46 leading to the flyers 27, 27' which are mounted on an annular ring 47 forming part of the enlarged portion 44. Disposed at points at right angles to the passages 46 are short spindles 48 carrying rollers 49 contained in recesses 50 in the enlarged portion 43. The rollers 49 are loosely mounted on the spindles 48, so that as the spindle 43 rotates the rollers fly outwards. Each roller 49 carries two flanges 51, 52 at the top and bottom respectively. The flange 51 engages with an annular depending race 53 rigidly fixed to the platform 10. The lower flange 52 engages with a similar annular race 55 carried by the frame 56 of the machine. Since the flanges 51, 52 are of the same size, the races 53, 55 are frictionally geared together, so that the upper race 53 is caused to remain stationary. As a result, the platform 10 of the bobbin 8 which is carried thereon, is caused to be held stationary while the spindle 43 and the flyers 27, 27' rotate to produce the same effect as that described with reference to Fig. 1.

Referring to Fig. 3 a method of doubling together a highly twisted thread with a thread to which no twist is imparted is shown. As generally indicated at 26, a driving device such as is illustrated in Fig. 1 or 2 is provided by means of which the flyers 27, 27' may be caused to rotate at high speed, while the platform 10 which carries bobbins of thread on brackets 9 is caused to remain stationary. In the arrangement shown, the untwisted thread comes from a bobbin 58 mounted on the same platform 10 as the bobbin 59 from which the thread to be highly twisted is drawn. The thread 60 coming from the bobbin 59 passes through a guide 61 down the flyer 27' to the hollow interior of the driving spindle 14, and thereby receives a number of turns of twist equal to twice the revolutions of the driving spindle. Inside the hollow spindle 14, the thread 60 meets the thread 62 which passes directly through the platform 10 and through the hollow spindle on which the platform 10 is carried, and is doubled with the thread 60 with a number of turns equal to the number of revolutions of the device to form a doubled thread 63. It will be seen that the thread 62 passes directly from a stationary bobbin straight out of the device, and that doubling is effected

by wrapping the loop of the thread 60 about the thread 62.

Referring to Fig. 4, the thread 65 receiving no twist is taken from an external package 66, while the thread 67 to be twisted to a high degree is taken from a package 68 mounted in the twisting device. The thread 65 passes into the hollow connecting piece 57 to which the flyers 27, 27' are attached, and then passes round the package 68 through the flyer 27 to the hollow interior of the spindle 14. The thread then passes through the axis of the package 68 back to the connecting piece 57. At this point the threads 65 and 67 meet, and pass together down the flyer 27' back to the interior of the hollow spindle 14 and thence out at the bottom of the spindle. Since the loop of the thread 65 contained in the flyer 27 rotates about the package 68, the thread 65 is wrapped round the thread 67 with a number of turns equal to the revolutions of the spindle. At the same time a twist is put into both the threads 65 and 67 equal also to the revolutions of the spindle. As the two threads 67 and 65 pass down the flyer 27, and are rotated together in a loop about the package 68, they are doubled together with an additional number of turns, also equal to the revolutions of the driving spindle, this further doubling having the effect of removing the twist already imparted to the thread 65, and further twisting the thread 67. Thus the final doubled thread 69 passing out of the bottom of the hollow spindle 14, consists of an untwisted thread 65 and of a thread 67 twisted to twice the revolutions of the twisting device, the two threads being doubled together with a number of twists equal to twice the revolutions of the twisting device.

In Fig. 5 an arrangement is shown for produc-

ing the same effect as that produced in the arrangement of Fig. 3, with the difference in method that the thread 62 which is not to be twisted is taken from the package 66 outside the device, and is led from the connecting piece 57 down the flyer 27 to the hollow interior of the spindle 14, where it meets the thread 60 which has passed down the flyer 27'. As in Fig. 3 the rotation of the loop of the thread 60 contained in the flyer 27' about the package 59 causes the thread 60 to be twisted to a number of turns equal to twice the revolution of the twisting device. The thread 62 passing down the flyer 27 does not receive any degree of twist, but is doubled together with the thread 60 to a number of doubling turns equal to the revolutions of the spindle.

What I claim and desire to secure by Letters Patent is:—

Method of doubling threads comprising drawing a thread through a looped path from a package in a twisting device, rotating the loop of thread so formed completely about the package so as to twist the thread during drawing, drawing a further thread from a supply outside the twisting device, passing such further thread around a looped path which rotates completely about the package within the twisting device, passing such further thread through the axis of said package, associating the further thread with the thread drawn from the package, and carrying the further thread along the looped path followed by the thread drawn from the package whereby the further thread, while not receiving any twist during the operation, is doubled with the thread drawn from the package to a degree equal to the degree of twist imparted to the thread drawn from the package.

WILLIAM POOL.
